FRANK A. HOWARD, OF ELIZABETH, NEW JERSEY.

GOLF CLUB.

Application filed November 2, 1927. Serial No. 230,416.

This invention relates to golf clubs of the type known as "drivers" and will be fully understood from the following specification and the appended drawing.

- 5 In the drawing Fig. 1 is a front elevation of a driver embodying the present invention;
 Fig. 2 is a side elevation;
 Fig. 3 is a top plan view;
 10 And Figs. 4 and 5 are side views of modified constructions.

The letter C represents the center of a theoretical sphere of radius R. The club head, designated H, is for purposes of analysis, assumed to be carved out of the body of the theoretical sphere, the striking face of the head, designated F, being formed by a portion of the surface of the sphere. The portion of the surface so utilized is a small 15 section of the periphery of the thick disc formed by parallel planes cutting the sphere to form circles of intersection of radius R' and R², as shown in Fig. 2. This provides the necessary upward slope or loft of the 20 striking face as shown in Figs. 1 and 3.

The club head is preferably formed of wood, as is ordinarily the case in clubs of this description. A striking face, sole piece, or weight, of metal, bone, gutta percha or 25 other material may be used, these matters having no connection with the present invention.

The shaft of the club, designated S, is preferably formed of steel, tubular in transverse section and slightly tapered or coned in longitudinal section. It is of curved form, as illustrated, but terminates in a straight handle section L. The projected axis of the 30 straight handle section passes through the center C of the theoretical sphere, as indicated in Figs. 1, 2, and 3, piercing the plane of the sole of the head H at a point some distance behind the striking face F.

The construction described is especially intended for the clubs known as "drivers" in which the angle A (Fig. 1) between the longitudinal plane through the shaft and the ground, or sole of the club head, is about 55° more or less. The construction 35 is also applicable to similar clubs of the type known as "brassies" and "spoons" in

which the angle A and likewise the loft or inclination of the striking face is somewhat different.

In the form of the invention illustrated by 55 the drawing, it will be noted that the shaft S and handle portion L appear to be straight in front elevation, which means that the curvature of the shaft is single, not double, the axis lying in a single longitudinal plane. 60 While sometimes desirable structurally, this is not necessary functionally. Functional requirements have to do with the relation between the projected axis of the handle and primarily the position and secondarily, the 65 conformation of the striking face.

By virtue of the relations established by the present invention, the club consists in effect of a sphere of such great diameter as to be almost plane-surfaced, as compared 70 with the golf ball, actuated by a straight handle which passes through the center of the sphere. The ball being addressed by the sphere, and the sphere being thereafter swung to strike the ball with a part of its 75 surface approximating the part used to address it, the sphere being at the time in motion in the direction of the intended flight of the ball, a straight normal flight results. Turning or twisting of the handle L upon 80 its own axis, as by inadvertent motion of the arms or wrists, results in the point of impact shifting on the striking face, within the limits fixed by the size of the face but not shifting upon the ball itself. Off-center impact 85 upon the ball, which results in the spinning motion which in turn produces the deviation from straight flight known as a "slice" or "hook" is thus obviated. Likewise, the swinging of the club in a direction not at 90 right angles to its axis, as by permitting the club head to lag behind the handle during the effective portion of the stroke, cannot of itself cause off-center impact upon the ball 95 as would be the case if the striking face had a single or cylindrical curvature or were plane.

The design of the present invention therefore permits certain angular latitude in the stroke without the resulting difficulties 100 which such angular variations give in the case of the clubs of the prior art.

A difficulty which is inherent in the club of the present invention lies in the fact that off-center impact upon the ball will result when there is longitudinal displacement of the club in the act of swinging, so that the club face F does not strike the ball in the direction of the radius of the theoretical sphere at the point of impact. The greater the radius of the theoretical sphere, the less the difficulty from this source, but the greater is the departure from normal construction in the matter of the angularity of the handle L , if the theory of the present design be followed exactly. It is not required, however, that the theory be followed with strict mathematical accuracy. The advantages of the invention may be retained in important measure by constructions in which the curvature of the face F is much less than that of the theoretical sphere, or is indeed practically non-existent, and the angularity of the handle L likewise smaller than would be required to cause its projected axis to pass through the center of curvature. Any angularity of the handle, even though small, is of importance in itself in that it gives a position of the arms which is more natural in many cases than the position required by a handle substantially in alignment with the face of the club head.

In Fig. 4 the head H^4 , including the face F^4 , is of standard or ordinary construction, except that the shaft S^4 enters the head nearer the back than the face of the club. The shaft S^4 is itself straight but the handle portion L^4 thereof is bent sharply, so that the projected axis of the handle pierces the plane of the sole of the club head at the point C^4 which is well back of the striking face of the club F^4 and indeed some distance back of the rear face of the club head.

In Fig. 5, the club head H^5 is of novel form in that the neck portion of the head into which the shaft enters extends rearwardly, laterally and upwardly, instead of only laterally and upwardly as in common practice. With this head there may be used a straight shaft S^5 with a straight handle L^5 in alignment therewith. The projected axis of L^5 , passing through the shaft pierces the plane of the sole of the club head at C^5 , which, as before, is well back of the striking face F^5 . That portion of the shaft which enters the club head is shown in dotted lines in this view, and designated SS^5 . As illustrated, it is bent at a sharp angle in order to extend the full length of the club head and emerge only at the sole.

The modified construction shown in Fig. 6 retains the advantage of the angular handle without otherwise departing from the conventional straight-shafted clubs of the prior art. In the construction of Fig. 5, there is no angularity of the handle but, through the use of the special form of club

head, the axis of the handle lies well behind the striking face.

While I have shown and described in some detail, forms of clubs embodying my invention and have stated the mathematical basis upon which some of the features of these clubs are designed, it will be understood that such details and the reasoning advanced in support of the designs are all for the purpose of making the invention more clear, and that the invention is not to be regarded as limited to the specific features shown nor as dependent upon the soundness of the reasoning advanced, save to the extent that such limitations or definitions of principles of design are included within the terms of the appended claims, in which it is my intention to claim all novelty inherent in the invention as broadly as is permissible in view of the prior art.

What I claim is:

1. A golf club of the driver type in which the plane of the sole of the club head is at an angle of approximately 55° to the shaft, comprising a head having a striking face, and a shaft secured thereto and forming a handle at its upper end, the downwardly projected axis of such handle portion of the shaft piercing the said plane at a point substantially behind the striking face.

2. A golf club of the driver type in which the plane of the sole of the club head is at an angle of approximately 55° to the shaft, comprising a head having a striking face, and a shaft secured thereto and forming a handle at its upper end, the downwardly projected axis of such handle portion of the shaft piercing the said plane at a point behind the rear face of the club head.

3. A golf club of the driver type in which the plane of the sole of the club head is at an angle of approximately 55° to the shaft, comprising a head having a convex striking face of generally spherical curvature, and a shaft secured thereto and forming a handle at its upper end, the downwardly projected axis of such handle portion of the shaft piercing the said plane at a point substantially behind the striking face.

4. A golf club of the driver type in which the plane of the sole of the club head is at an angle of approximately 55° to the shaft, comprising a head having a convex striking face of generally spherical curvature, and a shaft secured thereto and forming a handle at its upper end, the downwardly projected axis of such handle portion of the shaft passing through the approximate center of curvature of the said face.

5. A golf club of the driver type in which the plane of the sole of the club head is at an angle of approximately 55° to the shaft, comprising a head and an arcuate curved shaft secured thereto, the curve being rearward and such that the theoretical normal

shaft for the said head would constitute the chord of the arc of the actual shaft here defined.

6. A golf club of the driver type in which the plane of the sole of the club head is at an angle of approximately 55° to the shaft, comprising a head having a convex striking

face of generally spherical curvature and an arcuate curved shaft secured thereto, the curve being rearward and such that the projected axis of the handle portion of said shaft passes through the approximate center of curvature of the said face. ¹⁰
